UNITED STATES PATENT OFFICE.

ERNEST OLDENBUSCH, OF HOBOKEN, NEW JERSEY, ASSIGNOR TO KRON-HEIMER AND OLDENBUSCH COMPANY, A CORPORATION.

DESK FURNITURE.

SPECIFICATION forming part of Letters Patent No. 693,426, dated February 18, 1902.

Application filed April 27, 1901. Serial No. 57,692. (No model.)

To all whom it may concern:

Be it known that I, ERNEST OLDENBUSCH, a citizen of the United States of America, and a resident of Hoboken, in the county of Hudson and State of New Jersey, have invented certain new and useful Improvements in Desk Furniture, of which the following is a specification.

My invention relates to improvements in desk furniture; and the object of my invention is to provide a device of neat appearance and of durable and economical construction for use upon a writing-desk and in other places. I attain this object by the device illustrated in the accompanying drawings, in which—

Figure 1 is a view of the device complete. Fig. 2 is a view of the pen-rack member detached from the base, with the tongue *d* bent away to show the construction. Fig. 3 is a view of the stamp compartment or box. Fig. 4 is a view of the base, and Fig. 5 is a view of the sheet-metal blank from which the pen-rack member is formed.

Similar letters refer to similar parts throughout the several views.

I form my improved device as follows: I cut out a piece of sheet metal, as shown at Fig. 5, having counterpart projecting sides *b*⁷ and *b*⁸, 30 provided with corresponding indentations *b*¹ and *b*², *b*³ and *b*⁴, *b*⁵ and *b*⁶, and a tongue or flat spring *d*. The sides *b*⁷ and *b*⁸ may also be provided with lugs *e*¹, *e*², *e*³, and *e*⁴ for fastening the member to the base *a*. These indented sides *b*⁷ and *b*⁸ of this piece of sheet metal are bent up at approximately right angles to the central section *b*. The tongue or flat spring *d* is also bent up in front of the central section *b*, a section *d*² at the base of the tongue *d* being bent into a plane at a right angle to the central section *b*, the tongue *d* bent up beyond the edges of the sides *b*⁷ and *b*⁸, and the upper end of *d*² of the tongue *d* being bent outwardly and away from the central section *b*.

The base *a* may be made of any desired

material; but I prefer to stamp it out of sheet metal. This base *a* may be in the form of a tray, as shown, having a border or ornamental edge *i*, or it may be of any desired pattern. 50 A section is cut out at or near the center of the base or tray *a* and clips *a*¹, *a*², *a*³, and *a*⁴ provided for holding an ink-well *g*, as shown in Fig. 1.

The pen-rack may be attached to the base *a* by means of slots *f*¹, *f*², *f*³, and *f*⁴, cast in the base of the tray *a*, through which are passed the lugs *e*¹, *e*², *e*³, and *e*⁴, which being folded over hold the parts together. To the back of the central section *b* of the pen-rack 60 member may be attached a compartment *c*, of sheet metal, for holding postage or other stamps. This stamp-compartment *c* may be attached to the pen-rack by means of solder applied to its edges *c*¹, *c*², and *c*³ or in any 65 well-known manner. The cover *g*' of the ink-well *g* may be attached to the device by means of a ring *h* and chain *h*', if desired. As the upper end *d*' of the spring is bent outwardly, a pen or pencil may be readily 70 slipped down inside of the spring *d* and will be held by the spring at the indentations or sockets *b*¹ and *b*² or *b*³ and *b*⁴ or *b*⁵ and *b*⁶.

Having thus described my invention, what I claim is—

1. In a device of the character described a central section, two counterpart side sections having indented sides and a tongue extending up outside thereof substantially as shown and described.

2. In a device of the character described two sheet-metal members having counterpart indented edges and a spring extending up outside of such edges substantially as shown and described.

Signed at Brooklyn, New York, this 25th day of March, 1901.

ERNEST OLDENBUSCH.
